UNITED STATES PATENT OFFICE

ALEXANDER S. GREENSTEIN, OF NEW YORK, N. Y.

FUR STRETCHING DEVICE

Application filed September 9, 1930. Serial No. 430,638.

This invention relates to devices for stretching furs and like materials; to be used on pieces of such material being worked on and adapted to stretch a portion of the piece 5 worked on without affecting the rest thereof and without interfering with the operation done thereon.

Other objects of my invention are to provide a device of the character mentioned 10 which will be simple in construction, inexpensive, efficient in operation and easy to apply to the piece in question or to remove it therefrom.

My invention is mainly used on fur collars, bodies of fur coats along their waist lines or similar places, where it is desired to give shape or fullness to the piece in question without extra cuts, seams and so on.

In the drawing forming a part of this 20 specification:

Fig. 1 is a perspective view of my device as applied to a piece of fur, while

Fig. 2 is a perspective view of my device in an open position, and

Fig. 3 is a sectional elevation of a modification of my invention.

Referring now to the drawing by characters of reference, the numeral 10 indicates my device in general, being composed of two 30 elongated plate like elements or strips of metal 11 and 12. The two strips of material are connected to each other by a hinge device 13 of any appropriate construction so that the element 11 may be closed down upon the element 12. A wall or projection 14 rises from the center part of the plate 12, said projection being thin compared to its width and height and having an apex or highest 35 point 15 from which a longer edge 16 is descending to the surface of the plate 12 in a continuous curve outwardly toward the free end of the device, while a shorter edge 17 is descending to the plate 12 towards the hinge 40 joint between the two plates.

The upper plate 11 has a slot 18 provided in its center line, said slot being adapted to fit over and encircle the projection or wall 14 when the two parts are closed upon one 45 another and said slot being of a somewhat

larger width and length than said projection 14.

In use the base plate 12 is placed underneath the portion 19 of the fur 20 which is desired to be stretched and said portion of the fur is worked over the edge 16 as indicated in Fig. 1, stretched thereover, as at 19, after which the plate 11 is closed upon the fur, its slot 18 keeping said fur tightly stretched or locked over the wall 14. After 60 the necessary operations are done to the piece 20 and the same is cut to its size and shape as required, the device 10 will be released and removed therefrom and the added material or fullness resulting from the stretching at 65 19 will be arranged on said piece 20 so as to give it the desired rounded shape or fullness, as for instance those of a fur collar, or the waist region of a fur coat.

A modified construction of my device is 70 indicated in Fig. 3 in which the projection 14 is not permanently secured or an integral part of the plate 12, but it is a separate piece slidably arranged in a slot 21 in the plate 12, said slot running to the outside end 22 of the 75 plate 12, so that the projection 14 may be pulled entirely out of engagement with the plate 12 by sliding it completely out of said slot 21 at its open outer end and then another similar wall or projection 14 may be inserted 80 in its place into said slot 21, the various plates to be used with my device being of various heights and contours to fit all of the operations and pieces of work in question.

Holes 23 may be provided in the base plate 85 12 to accommodate securing screws or nails for the same, in case it is desired to permanently secure my device to a worktable or the like.

It will be understood that changes and 90 variations may be made in the various parts and combinations of my device and I hereby reserve all and any rights that I may have to all such changes and variations as are within the spirit of the invention and the scope of 95 the appended claims.

What I claim as new, is:

1. In a device for stretching furs and like materials, two elongated plate like elements hinged together at one end; a thin wall along 100

the center line of one of said elements, the other element having a slot adapted to receive said wall and encircle the base of the same when said second plate is closed down upon said first plate, whereby a portion of said fur or like material stretched or folded over said wall may be closed upon and tightly kept thereon upon the closing of said second plate, said wall being a separate piece of material secured in a longitudinal slot in its plate and slid able into and out of said slot in a longitudinal direction for the purpose of exchanging said wall.

2. In a device for locally stretching furs and the like, an upstanding wall adapted to be placed underneath the portion of the fur to be stretched, and a frame encircling said wall and being adapted to close on the fur and tightly stretch the same on said wall, the greatest height of said wall being several times that of its thickness.

3. In a device for locally stretching furs and the like, an upstanding wall adapted to be placed underneath the portion of the fur to be stretched, and a frame encircling said wall and being adapted to close on the fur and tightly stretch the same on said wall, the greatest height of said wall being several times that of its thickness, said wall having an inclined upper edge.

4. In a device for locally stretching furs and the like, an upstanding wall adapted to be placed underneath the portion of the fur to be stretched, and a frame encircling said wall and being adapted to close on the fur and tightly stretch the same on said wall, the greatest height of said wall being several times that of its thickness, said wall having an inclined upper edge, said upper edge at no point being above the straight line connecting the highest and lowest points thereof.

5. In a device for locally stretching furs and the like, an upstanding wall adapted to be placed underneath the portion of the fur to be stretched, and a frame encircling said wall and being adapted to close on the fur and tightly stretch the same on said wall, the greatest height of said wall being several times that of its thickness, said wall having a declining upper edge from the highest point thereof to the level of its base, a hinge device between said frame and said wall, said hinge being at the portion of the device nearer to the high end of the wall.

55 Signed at New York in the county of New York, and State of New York this 14th day of August, 1930.

ALEXANDER S. GREENSTEIN.
